Richard D. Oliver

ATTORNEY.

UNITED STATES PATENT OFFICE.

JOSEPH SELWAY ADAMS, OF GREENWOOD, ARKANSAS.

TRACK DEVICE.

Application filed September 22, 1921. Serial No. 502,447.

To all whom it may concern:

Be it known that I, JOSEPH S. ADAMS, a citizen of the United States, residing at Greenwood, in the county of Sebastian and 5 State of Arkansas, have invented certain new and useful Improvements in Track Devices, of which the following is a specification.

This invention relates to track devices and 10 more particularly to a novel and improved switching device adapted for use in that type of track known as "industrial rail-ways," and more especially with the tracks employed in mines.

15 The primary object of the invention is to provide a device that may be placed between the switch point and the inside of the main line rail to positively guide the wheels of the car onto the switch and prevent the possibility of derailment caused by a bent or 20 sprung switch point.

A further object of the invention is to provide a metal switching device placed between the inside of the main line track and 25 the switch point of the side track to positively guide the car wheels onto the switch and to prevent the switch point from being forced out of position.

A third object of the invention is to provide a track device that is adapted for use 30 with either a right hand or left hand switch.

With the above and other objects in view as will be hereinafter apparent, the invention consists in general of certain novel de- 35 tails of construction and combinations of parts hereinafter fully described, illustrated in the accompanying drawings and specifically claimed.

In the accompanying drawings like char- 40 acters of reference indicate like parts in the several views, and:—

Figure 1 is a plan view of a portion of the track and switch showing my device applied thereto.

45 Figure 2 is a perspective view of the switching device.

Referring now to the drawings A designates the main track consisting of rails 5 and 6, the side track is designated by B 50 which leads to the main track and 7 and 8 indicate the switch points operating in the well known manner to switch the cars onto either track desired.

It is found in actual practice that the 55 switch point becomes sprung or injured by

the heavy service and poor road bed to which this type of track is subjected and that frequent derailment of the cars is caused by the flange of the wheels following between the main track and the switch point 60 when set to take the siding.

To overcome this condition I have provided a novel and improved device which is designated as a whole by 9, consisting of a rectangular section 10, a wedge shaped end 65 portion 11 terminating at one end in a sharp edge 12 and having a shoulder, or abutment 13 at the other end, the upper and lower surfaces of the device being parallel. In practice, the straight side of the device is 70 placed against the inner face of the main track in such a position that the switch point lies back of and against the face or shoulder 13 and the point 12 of the triangular section lies close against the main line 75 track in such a position that the flange of the wheel will ride out and upon the triangular section and thereby be guided upon the switch point without danger of derailment.

80 By having the upper and lower faces parallel I am enabled to use this device equally as well for a right or left hand switch by turning the switching device over, bringing the point 12 from left to right, or 85 right to left.

There has thus been provided a simple and efficient device of the kind described and for the purpose specified.

It is obvious that minor changes may be 90 made in the form and construction of the invention without departing from the material spirit thereof. It is not, therefore, desired to confine the invention to the exact form herein shown and described, but it is 95 desired to include all such as properly come within the scope claimed.

Having thus described the invention what is claimed as new, is:—

A device of the kind described consisting 100 of a single member rectangular in cross section and having upper and lower faces of identical shape and parallel throughout, one end of said member being tapered laterally to form a sharp wedge with its edge at one 105 extremity of the member and its butt about centrally thereof, the other end of said member being of less width than the butt of the wedge and of uniform width throughout, one side of the last mentioned end lying in 110

the plane of one side of the wedge, said member being adapted for use with either face uppermost and with the wedge pointing in either direction whereby said member 5 may be positioned between either a right or left hand switch point and a main line rail on either side of a track.

In testimony whereof I affix my signature in presence of two witnesses.

JOSEPH SELWAY ADAMS.

Witnesses:

DAN C. McDONALD,
C. B. RYAN.
